Primary Examiner — Catherine Tuttle(74) *Attorney, Agent, or Firm* — Sterne, Kessler, Goldstein & Fox P.L.L.C.(57) **CLAIM**

The ornamental design for a bottle, as shown and described.

DESCRIPTION

FIG. 1 is a top front perspective view of a bottle showing my new design;

FIG. 2 is a bottom rear perspective view thereof;

FIG. 3 is a front view thereof;

FIG. 4 is a rear view thereof;

FIG. 5 is a right side view thereof, the left side being a mirror image thereof;

FIG. 6 is a top view thereof; and,

FIG. 7 is a bottom view thereof.

The dashed broken lines in the Figures show portions of the bottle that form no part of the claimed design.

The surface lines in the Figures show contour and not surface ornamentation.

The dot-dash broken lines in FIG. 2 and the area within show portions of the bottle that form no part of the claimed design.

1 Claim, 7 Drawing Sheets(56)
